UNITED STATES PATENT

GEORGE RIELLY, OF SANTA ROSA, CALIFORNIA

CUSHION FOR RAILROAD-RAILS.

1,171,250.

Specification of Letters Patent. Pat

Application filed September 14, 1914. Serial No. 861,494

To all whom it may concern:

Be it known that I, GEORGE RIELLY, a citizen of the United States, residing at Santa Rosa, in the county of Sonoma and State 5 of California, have invented a certain new and useful Improvement in Cushions for Railroad-Rails, of which the following is a specification.

My invention relates to that class of devices which are designed to be used in connection with concrete ties.

It is a well-known fact that the most serious objection to concrete ties is owing to their inability to cushion the blow of the 15 wheels of the railroad rolling stock, the result being that although preferable to wooden ties in many instances, they are not generally used for this reason.

My invention has for its object to provide a cushion to be used in connection with my improved fastening device for concrete ties described in my Patent #1097880, May 26, 1914, and has for its object to interpose a resilient cushion preferably 25 formed of metal intermediate the rail and the tie which will absorb the effect of the blow without damage, either to the coach or the tie.

My means of accomplishing the foregoing 30 objects may be more readily understood by having reference to the accompanying drawings which are hereunto annexed and are a part of this specification, in which:

Figure 1, is a vertical sectional view of 35 my invention showing a fragmentary portion of a concrete tie, the view being taken on the line $x-x$, in Fig. 2. Fig. 2, is a top or plan view of the device. Fig. 3, is a perspective view of one of the cushions.

Similar reference numerals refer to similar 40 parts throughout the entire description.

As shown in the drawings, 1 indicates a T-rail which is mounted upon the concrete tie 2 being secured in position by means of 45 the clamping device which is the one shown in the hereinbefore mentioned patent, and which consists of three sections, two of which, 6 and 7, are provided with straight sides 8, and tapering sides 9 and 10. The 50 third section 11, is provided with parallel sides which are adapted to engage the tapering side 9 of the section 7, and the end wall 12, of the recess 13, which is formed in the concrete tie 2.

The section 7, is provided with an upwardly extending stem 14, and is provided

with threads designed internal nut 15, which

The upper part of with an outwardly ex is engaged by the lov 17 of the T-rail 1, w. of section 6, engages recess 13. The result that when the nut 15 tion 7, is drawn upwa adjacent sections outv holding them in posit the rail firmly in posit

The inner face of t straight as at 18 to pi movement of the rail

Intermediate the lo 17 of the rail 1, and t I mount a flat plate above this, I mount m preferably formed of : shown in Fig. 3, this s two slots, or recesses, adapted to surround for securing the rail to be of greater depth t vice, so as to permit th when weight is put u pressure against the cl

It will be apparent the art that inasmuc cushion for every tie, cated approximately will be substantially each car, and the spir lated to possess a stre half of the distance b of the plate 20 or the u 19, as otherwise the would be lost.

By providing the p surface of the tie, I e abrading movement o means of the spring, terially increasing the

Having described n regard as new and des ters Patent is:

1. The combination means for securing a wear plate positioned of the tie and having o securing means, a curv ing relatively straigh

the wear plate, said straight portions having slots adapted to accommodate the securing means, said slots being of a length to allow movement of the spring plate without the 5 walls of the slots engaging the fastening means.

2. The combination with a concrete tie, of means for securing a rail to the tie, a flat wear plate positioned on the upper surface 10 of the tie and having openings to receive the securing means, a spring plate having a substantially flat rail seat, and substantially flat wear plate engaging portions, curved portions connecting the rail engaging sections

and wear plate engaging portions to provide resiliency, each of the plates having 15 openings to receive the rail fastening means, the openings of the spring plate extending from the edges thereof and terminating within the flat surface of the rail engaging portion to allow movement of the spring plate with relation to the fastening means. 20

In testimony whereof, I have signed the foregoing specification.

GEORGE RIELLY.
